(57) **CLAIM**

We claim the ornamental design for the trimmer, as shown and described.

DESCRIPTION

FIG. 1 is a perspective view of a trimmer shown in an open configuration;

FIG. 2 is a left side view of the trimmer shown in a closed configuration;

FIG. 3 is a top view thereof;

FIG. 4 is a bottom view thereof;

FIG. 5 is an end view thereof;

FIG. 6 is an opposite end view thereof;

FIG. 7 is a left side view of the trimmer shown in an open configuration;

FIG. 8 is a top view thereof;

FIG. 9 is a bottom view thereof;

FIG. 10 is an end view thereof; and,

FIG. 11 is an opposite end view thereof.

The right side views of the trimmer are mirror images of the respective left side views.
